By *Silas B. West*
Attorney.

ably wrapped on said cylinder and electrical-
ly insulated therefrom, a sheet 18 of suitable
insulating material being shown about said
cylinder within the coil 17. One end of
5 the coil 17 is operatively connected with the
metal of the cylinder 14 and the other end of
said coil connects with a binding post 19
carried by and insulated from the plate 11,
a conductor 20 operatively connecting said
10 binding post through suitable switch mecha-
nism (not shown) with a source of electrical
energy, so that, when the other pole of said
source of energy is connected with the metal-
lic parts of the internal combustion engine or
15 primer, a circuit may be established through
the coil 17 to heat said coil and consequently
heat the cylinder 14 and its contents. Pos-
itioned in and opening through the plate 11
above the cylinder 14 is a mixing valve 21,
20 which valve comprises a block of suitable
material fitted closely into an aperture in said
plate and formed with a central, axial bore
and a plurality of auxiliary holes each at an
angle with said axial bore. A needle valve
25 housing 22 is positioned within the shell 10
in operative communication with the central
bore of the mixing valve 21 and is operatively
connected with the cylinder 14 by means
of a suitable tube 23, so that passage is pro-
30 vided from the interior of said cylinder
through said tube 23, housing 22 and the cen-
tral bore of the mixing valve 21. In thread-
ed engagement through and extending at one end
35 beyond the inner end of said housing 22
is mounted a needle valve 24 rotatably adjust-
able relative to said housing to open or close
the passage above described, the end of the
needle valve without said housing being an
40 regular in cross section for a purpose which
will hereinafter appear. Axially aligned
with the needle valve housing an open-ended
sleeve 25, preferably cylindrical in form, is
fixed at one end to and opens through the
45 plate 12 for positioning within the shell 10.
Fitted closely within and slidably axially rel-
ative to the sleeve 25, a hollow plunger valve
26 formed with an inner open end and an
outer closed end is mounted in closing rela-
50 tion with the outer end of said sleeve. The
outer end of the valve 26 is preferably pro-
vided with an annular flange adapted to close
against the plate 12 and limit inward move-
ment of said valve and a gasket 27 is inter-
55 posed between said flange and the plate 12 to
effectively seal the joint there-between when
said valve is in closed position. A retractile
coil spring 28 operatively connects the outer
end of the valve 26 with the inner end of the
60 sleeve 25 and acts to normally position said
valve at the innermost limit of its range of
travel and hence in closing relation with
the plate 12. The walls of the valve 26 adja-
cent its closed end are provided with ports
65 or openings 29 which act when the said valve
is moved outwardly of the sleeve 25 to pro-

vide a passage wherethrough air may pass
to the interior of the shell 10. A control rod
30 is swiveled to and extends through the
closed end of the valve 26 and terminates
within the shell 10 in a sleeve portion 31
70 formed with an angular bore wherein is tel-
escopically received the outer end of the
needle valve 24, whereby rotation of the con-
trol rod 30 may be transmitted for adjust-
ment of said needle valve. The outer por-
75 tion of the rod 30 is extended through suit-
able guides and fittings to a location within
convenient reach of an operator where it ter-
minates in a button or similar operating de-
vice 32.

The mixing valve 21 may be operatively
connected in many suitable manner with the
intake ports of an internal combustion en-
gine a preferred means of effecting such con-
nection being illustrated. As shown, a con-
nector 33, formed with a central bore adapt-
ed to register with the bore of an intake mani-
fold is provided with a side opening throat
34 communicating with its central bore and
is adapted to be clamped against suitable
gaskets between the throat 35 of a carburetor
and the end 36 of the intake manifold to
which the carburetor normally attaches the
end of the throat 34 being operatively con-
nected with the outer side of the mixing valve
21 by means of a conduit 37 extending there-
between which conduit may well be of flexible
end beyond the inner end of said housing 22
35 may be provided on the plates 11 and 12 for
attachment to suitable brackets or structural
elements to support the primer in the de-
sired relation with an internal combustion
needle valve without said housing being an
40 engine.

As indicated at 39 the inner wall of the
45 shell 10 may be covered with asbestos or sim-
ilar heat insulating material to minimize heat
sleeve 25, preferably cylindrical in form, is
fixed at one end to and opens through the
50 plate 12 for positioning within the shell 10.

In the practical operation of the improved
55 primer constructed, arranged and connected
as above described, the needle valve 24 and
plunger valve 26 are normally closed and the
primer then inoperative. When desired to
use the primer, the needle valve 24 is rotated
60 to open position to permit the desired amount
of fuel flow and the rod 30 is actuated to open
the valve 26 the desired amount, whereupon
air will flow under the suction induced by
operation of the internal combustion engine
65 through the ports 29, valve 26, sleeve 25, shell
10, mixing valve 21, conduit 37 and throat
70 34 into the intake passage of said engine,
which air, as it passes through the valve 21,
meets with and is thoroughly mixed with
fuel vapor from the central bore of said valve.

The liquid fuel fed to the cylinder 14 through
75 the pipe 15 is heated by the coil 17 so that
only warm vapor is drawn to the valve 21
through the housing 22 and passage 23, the
coil 17 further serving to heat the interior
80 of the shell 10 so that the incoming air will
85 be heated as it passes through the mixing valve
21. The walls of the valve 26 are provided
with ports 29 which act when the said valve
is moved outwardly of the sleeve 25 to pro-

be warned. It is the function of the valve 21 to thoroughly agitate the mixture passing therethrough and thus produce a highly combustible fuel charge. Release of the rod 30 permits the spring 28 to close the valve 26 and arrest operation of the primer, whether or not the needle valve be closed.

Since infinite changes in the specific form, construction and arrangement of the elements shown and described may be had without departing from the spirit of the invention, I 10 wish to be understood as being limited solely by the scope of the appended claims.

I claim as my invention:—

1. A primer for internal combustion engines comprising a housing, a mixing valve in one wall of said housing, separate air and fuel supply means communicating with said valve through said housing, electrical heating means within said housing operable to simultaneously heat the air and fuel furnished by said supply means prior to their admixture, and means operatively connecting said mixing valve with the intake of an internal combustion engine.

2. A primer for internal combustion engines comprising a housing, a mixing valve in one wall of said housing, separate air and fuel supply means communicating with said valve through said housing, adjustable means operable to control the amounts of air and fuel fed through said supply means, a single electrical heating unit within said housing arranged to simultaneously heat the air and fuel furnished by said supply means prior to their admixture, and means operatively connecting said mixing valve with the intake of an internal combustion engine.

3. A primer for internal combustion engines comprising a normally closed housing, means operatively connecting the interior of said housing with the intake of an internal combustion engine, a mixing valve positioned at the junction of said housing and connecting means, fuel supply means communicating through said housing with said mixing valve independently of said fuel supply means, a single electrical heating unit within said housing arranged to simultaneously heat the air and fuel fed through said supply means prior to their admixture, and adjustable means operable to control the flow through said air and fuel supply means.

4. A primer for internal combustion engines comprising a normally closed housing, means operatively connecting the interior of said housing with the intake of an internal combustion engine, a mixing valve positioned at the junction of said housing and connecting means, a supplementary chamber within and sealed from said housing, a fuel supply line communicating with the interior of said supplementary chamber, a valve-controlled

passage between said supplementary chamber and said mixing valve, adjustable air supply means communicating through said housing with said mixing valve, manually-operable means for adjusting the flow of air and fuel to said mixing valve, and an electrical heating unit positioned about said supplementary chamber and operable to simultaneously heat the air and fuel fed through said housing prior to their admixture.

5. A primer for internal combustion engines comprising a normally closed housing, means operatively connecting the interior of said housing with the intake of an internal combustion engine, a mixing valve positioned at the junction of said housing and connecting means, valve-controlled fuel supply means communicating through said housing with said mixing valve, an open-ended sleeve carried within and opening through one wall of said housing, a valve slidable in and normally closing the outer end of said sleeve, spring means engaging between said sleeve and slidable valve to normally position the latter in closing relation with said sleeve, manually-operable means axially movable to adjust said slidable valve and rotatable to control the flow of fuel to said mixing valve, and an electrical heating unit within said housing arranged to simultaneously heat the air and fuel fed through said housing prior to their admixture.

6. A primer for internal combustion engines comprising a normally closed housing, means operatively connecting the interior of said housing with the intake of an internal combustion engine, a plate transversely of and obstructing said connecting means, an axial bore in said plate, valve-controlled fuel supply means communicating through said housing with said axial bore, a plurality of bores in said plate in angular relation with said axial bore, valve-controlled air supply means communicating through said housing with said latter bores, and an electrical heating unit within said housing arranged to simultaneously heat the air and fuel fed through said housing prior to their admixture.

7. In a primer for internal combustion engines having an air chamber operatively connected with the intake of an internal combustion engine, a mixing valve between said air chamber and engine intake, a fuel chamber within said air chamber operatively connected with said mixing valve and manually-operable control means for regulating the flow of air and fuel to said mixing valve, means for simultaneously heating the air and fuel fed to said mixing valve prior to their admixture, said means comprising a coil of resistance wire about the exterior surface of said fuel chamber and an electrical circuit operatively including said coil.

8. In a primer for internal combustion en-

gines, the operative combination of a mixing valve, independent air and fuel supply means communicating with said mixing valve, manually-adjustable control means operable to regulate the flow of air and fuel to said mixing valve, electrical means arranged to simultaneously heat the air and fuel fed to said mixing valve prior to their admixture, and means connecting said mixing valve with the intake of an internal combustion engine.

In witness whereof I affix my signature.

JAMES C. GOVER.
